UNITED STATES PATENT OFFICE.

JAMES L. WRAY, OF KEWANEE, ILLINOIS.

WATER-ELEVATING APPARATUS.

1,068,197.

Specification of Letters Patent. Patented July 22, 1913.

Application filed August 5, 1912. Serial No. 713,411.

To all whom it may concern:

Be it known that I, JAMES L. WRAY, a citizen of the United States, residing at Kewanee, in the county of Henry and State 5 of Illinois, have invented a new and useful Water-Elevating Apparatus, of which the following is a specification.

This invention relates to water elevating apparatus and is more particularly an improvement upon the structure disclosed in Patent No. 955,301 issued to me on April 19, 1910.

One of the objects of the invention is to dispense with stuffing-boxes in the sub- 15 merged tanks and at other points in the apparatus where leakage is apt to occur when the parts become worn and which necessitate tightening in order to permit the efficiency of the apparatus to be maintained 20 constant.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed, with- 30 out departing from the spirit of the invention.

In the accompanying drawings the preferred form of the invention has been shown.

35 In said drawings:—Figure 1 is a vertical section through the apparatus. Fig. 2 is a section on line A—B Fig. 1. Fig. 3 is a section on line C—D Fig. 1.

Referring to the figures by characters of 40 reference 1 and 2 designate tanks adapted to be submerged and each of which has a water inlet 3 at its inner end provided with a suitable check valve 4. Water outlet pipes 5 extend upwardly from the lower 45 ends of the tanks 1 and 2 and are preferably provided with check valves 6 whereby return flow of water from the pipes to the tanks is prevented. The pipes 5 are adapted to convey water to the point of use.

50 Extending upwardly within each of the tanks 1 and 2 from a point adjacent the bottom thereof, is a pipe 7 provided, at its lower end, with a valve 8 which normally closes the lower end of the pipe, said valve 55 being held in closed position in any suitable manner, as by means of a weighted lever 9

or the like. A float 10 is mounted to slide on the pipe 7 and is adapted, when in its lowermost position, to contact with the valve 8 and push it downwardly off of its 60 seat. For this purpose the float may be provided with opposed arms 11 or any other suitable means extending downwardly from the float and adapted to move against the valve 8 so as to unseat it. 65

The means for controlling the admission of air under pressure to the respective tanks 1 and 2 includes a cylinder 12 which can be placed either vertically or horizontally as desired, and can be located at any de- 70 sired distance from the tanks.

Arranged within the cylinder is a tubular member 13 which can be made up of sections, as shown, and secured to this member adjacent its ends, are outer piston heads 75 14 and 15 while secured to the tubular member 13 and between the heads 14 and 15 are inner piston heads 16 and 17 respectively. Thus a central compartment 18 is formed between the piston heads 16 and 17 and end 80 compartments 19 and 20 are formed between the heads 14 and 15 and the heads 16 and 17 respectively. One or more openings 21 are formed in the tubular member 13 and discharge into the compartments 19 and 20. 85 Each of these compartments 19 and 20 has an outlet or exhaust opening 22 through which fluid is free to pass into an exhaust pipe or passage 23 located outside of the cylinder 12. A pipe 24 extends from the 90 top of the cylinder 1 and opens in the cylinder 12 at one side of the center thereof while another pipe 25 extends from the top of tank 2 and opens into the cylinder at the other side of the center thereof. The 95 two pipes 7 open into the respective ends or heads of the cylinder 12.

Mounted in the tubular member 13 is a movable rod 26 extending longitudinally of the member 13 and held in proper position by spring guides 27 or the like. This rod is provided at its ends with tapered valves 28 and 29 respectively adapted to be alternately seated upon the respective ends of the tubular member 13 during the reciprocation of 100 the piston as hereinafter set forth.

105 It is to be understood that air is to be admitted under pressure to the cylinder 12 through a supply pipe 30 and that the tanks 1 and 2 are to be completely submerged in the body of water from which the supply is 110 to be drawn.

- Assuming that water has been withdrawn through pipes 5 from the apparatus until the float 10 in tank 1 has moved downwardly against the valve 8 so as to open it, as shown in Fig. 1, it will be understood that as soon as this valve is opened, the air which has been entering the top of the tank 1 under pressure from pipe 24, compartment 18, and pipe 30, will cause a portion of the small remainder of water in the tank 1 to flow upwardly past the open valve 8 into pipe 7 and thence against the piston head 15. As the valve 29 has already been closed by coming against one of the heads of the cylinder 12, it will be seen that the pressure of water against the head 15 will cause the tubular member 13 and all of the piston heads to move toward the other head of the cylinder. The water contained between head 14 and the adjacent head of the cylinder 12 will escape back into the tubular member 13 and thence through the openings 21 into the compartments 19 and 20 and outwardly from the cylinder 12 through the openings 22 and the passage 23. As the tubular member 13 and the piston heads are thus shifted, the valve 28 is ultimately brought against the cylinder head in the path thereof so as to close against the adjacent end of the tubular member 13, this movement causing the other valve 29 to become unseated. At the same time the pipe 25 is placed in communication with the compartment 18, the pipe 24 is placed in communication with the compartment 20, as will be apparent. Thus it will be seen that the pressure of air within the tank 1 will be cut off and said air will, instead, be free to escape from pipe 24 into compartment 20, thence through opening 22 into the exhaust passage 23. Water will therefore be free to rise within the tank 1 and the float 10 will move upwardly in said tank thus permitting valve 8 to again become seated upon the lower end of the pipe 7. While tank 1 is thus being filled, the air pressure has been diverted by the shifted pistons so as to pass from pipe 30 and the compartment 18 into the pipe 25 and thence to the top of tank 2. Thus, when it is desired to draw off water from pipe 5, the pressure of air upon the water in tank 1 will cause a portion of the water to flow from said tank by way of its pipe 5, the water continuing to exhaust from this tank whenever the outlet of pipe 5 is open. Float 10 gradually lowers as the water is drawn off and ultimately moves against and opens the valve 8 whereupon the compressed air in the tank 2 will cause a portion of the water to move upwardly in pipe 7 so as to enter cylinder 12 and press against the piston head 14. The various piston heads in the tubular member 13 will thus be shifted and the operation hereinbefore described will be reversed, whereby

pressure will be transferred to the cylinder 1 and cut off from cylinder 2 and said cylinder 2 permitted to fill through the valved inlet 3.

It will be apparent that by providing means such as described, it becomes unnecessary to extend rods or other movable parts into the submerged tanks 1 and 2 and consequently to use stuffing boxes for the purpose of preventing leakage. Stuffing-boxes have been found objectionable in that they soon become worn and it is therefore necessary to readjust them in order to prevent leakage. In view of the fact that the tanks are usually submerged at the bottoms of wells and other inaccessible bodies of water, it will be apparent that any structure necessitating adjustment of stuffing-boxes or the like is very objectionable.

What is claimed is:—

1. The combination with tanks adapted to be submerged and having valved inlets, and outlet pipes extending from the lower portions of the tanks, of a cylinder, a tubular member mounted for reciprocation therein, connected valves for alternately closing the respective ends of the tubular member, spaced pistons secured to the tubular member and forming a central compartment and end compartments therebetween, means for directing air constantly under pressure into the central compartment, pipe connections between the cylinder and the upper ends of the tanks, said pipes being placed successively into communication with the central compartment during the reciprocation of the pistons, each of said last named pipes, when out of communication with the central compartment, being in communication with one of the end compartments, there being means for maintaining communication at all times between the end compartments and the tubular member, pipes extending from the lower portions of the tanks for directing fluid under pressure into the respective ends of the cylinder, valves for normally closing said pipes at their inlet ends, and floats within the tanks for opening the valves when the contents of the tanks are lowered to a predetermined level.

2. The combination with separate tanks having valved inlets and outlet pipes extending from the tanks, of a cylinder, a tubular member mounted for reciprocation therein, spaced piston heads secured to the member and forming a central compartment and end compartments therebetween, said end compartments being constantly in communication with the interior of the tubular member, there being exhaust openings in constant communication with the end compartments, connected valves adapted to be successively seated against the respective ends of the tubular member, means for di-

recting air under pressure into the central compartment, means for placing said central compartment in communication with the tanks successively during the reciprocation of the tubular member, said means likewise serving to place the end compartments successively into engagement with the tanks during the reciprocation of the tubular member, and float controlled valved means within the tanks for directing fluid under pressure into the respective ends of the cylinder to actuate the tubular member and the piston heads.

3. In water hoisting apparatus, a controlling member including a cylinder having pressure inlets at the ends thereof, a tubular member mounted for reciprocation in the cylinder, spaced piston heads secured thereto and movable therewith and forming therebetween a central compartment and end compartments, there being exhaust openings in the cylinder constantly in communication with the end compartments; means for constantly directing air under compression into the central compartment, and pipes extending from the cylinder and adapted successively to be placed in communication with the central compartment to permit the escape of pressure to the point of use and to be brought successively in communication with the end compartments to permit the exhaust of pressure after use, said compartments being constantly in communication with the tubular member, and connected valves adapted to alternately close the ends of the tubular member.

4. In water hoisting apparatus, controlling mechanism including a cylinder hav-

ing pressure inlets at the ends thereof, a tubular member mounted for reciprocation, 40 piston heads movable with said member and forming therebetween a central compartment and end compartments, said end compartments being constantly in communication with the tubular member, connected 45 valves for alternately closing the respective ends of the tubular member, means for directing fluid under pressure into the central compartment at all times during the reciprocation of the tubular member, there being 50 exhaust openings constantly in communication with the end compartments, and separate pressure outlets each adapted to be placed successively in communication with one of the end compartments and with the 55 central compartment.

5. In a pumping device the combination of a cylinder including a hollow piston-rod, a piston at each end of the latter, an air inlet and an exhaust port in the wall of the 60 cylinder, a pressure tank with which the cylinder is connected, pistons mounted upon the piston-rod and adapted to control the air entering and leaving said cylinder, a valve rod lying in the bore of the piston-rod and 65 including a valve at each end, there being an opening in the wall of the piston-rod inward from the first described piston.

In testimony that I claim the foregoing as my own, I have hereto affixed my signature in the presence of two witnesses. 70
